UNITED STATES PATENT OFFICE.

ANDREW J. CARMICHAEL, OF NEW HAVEN, CONNECTICUT, ASSIGNOR TO THE GREIST MANUFACTURING COMPANY, OF NEW HAVEN, CONNECTICUT, A CORPORATION OF CONNECTICUT.

DESIGN FOR A PORTABLE ELECTRIC LAMP.

Application filed August 20, 1928. Serial No. 27,888. Term of patent 7 years.

To all whom it may concern:

Be it known that I, ANDREW J. CARMICHAEL, a citizen of the United States, and a resident of New Haven, in the county of New Haven and State of Connecticut, have invented a new and original Design for a Portable Electric Lamp, of which the following is a specification, reference being had to the ac-

companying drawing, forming part thereof.

The figure shows the lamp in side elevation.

I claim:

The ornamental design for a portable electric lamp substantially as shown.

New Haven, Connecticut, August 16th, 1928.

ANDREW J. CARMICHAEL.
